PAPER DISPENSING CABINET

Henry L. Samson, New York, N. Y., assignor to
 National Paper Products Company, San Francisco, Calif., a corporation of California

Application March 7, 1934, Serial No. 714,463

3 Claims. (Cl. 312—62)

This invention relates to a cabinet for containing and dispensing paper towels, toilet tissue, paper napkins, and the like.

Several types of cabinets for containing and dispensing paper towels, and like articles, are in common use. Such cabinets are usually provided with a narrow dispensing slot which is located in the bottom of the cabinet. Due to the position and the narrowness of the slot, several difficulties are encountered. For example in such containers the towels and other articles to be dispensed are stacked one on top of the other over the slot, thereby causing the entire weight of the stack to be imposed on the bottom-most towel, thus producing excessive friction with consequent tearing of the towels, particularly when withdrawn by wet hands. Again, when a large quantity, say one hundred and fifty towels, or more, are placed in such a cabinet, the weight upon the discharge slot is such that unless rollers are inserted in the bottom of the cabinet much waste results. Again, when the thread of the interleaving between the towels is lost, it is difficult or impossible to feed the next towel through the slot unless a pencil or knife, or similar contrivance, is used to pull the towel through the slot.

The object of the present invention is generally to improve and simplify the construction and operation of dispensing cabinets by which the above objections are overcome; and particularly to provide a cabinet in which the towels are adapted to be supported either on their edges or on their ends so as to reduce friction due to weight to a minimum; to provide a cabinet which employs a comparatively wide dispensing slot at the front rather than in the bottom of the cabinet so as to permit ready withdrawal of the towels even though the interleaving thread should be lost; to provide a cabinet which permits the use of a single or multiple compartments so that two users can withdraw towels simultaneously; to provide a cabinet which may be positioned with the dispensing slot either in a vertical or horizontal position; to provide an automatic follower plate whereby towels are moved forward and kept in position against the front dispensing slot, said follower plate being operable when the cabinet is placed in a horizontal or vertical position; and further, to provide a cabinet which is adapted to receive and dispense paper towels and like articles of single or a multiple fold form, whether they be interleaved or not.

55 The paper dispensing cabinet is shown by way

of illustration in the accompanying drawings, in which—

Fig. 1 is a perspective view of the paper dispensing cabinet showing the lower cover member in open position.

Fig. 2 is a central vertical cross section of Fig. 1.

Fig. 3 is a horizontal section taken on line III—III of Fig. 2.

Fig. 4 is a perspective view of the same cabinet shown in Figs. 1 to 3, the only difference being that the cabinet is placed with the dispensing slot in a vertical position.

Fig. 5 is a vertical cross section taken on line V—V of Fig. 4.

Fig. 6 is a diagrammatic view showing a single fold interleaved paper towel.

Figs. 7 and 8 are diagrammatic views showing multiple folded towels and like paper articles.

Referring to the drawings in detail, and particularly Figs. 1 to 3, A indicates the back panel of the cabinet, 2—2 the sides, and 3 and 4 the top and bottom sections, respectively. The sides of the cabinet are cut angularly, as indicated by the lines 5—5, making each side widest at its central portion and narrower at each end. This is an advantage as it produces greater accessibility when refilling the cabinet as will hereinafter be described.

The cabinet is divided into two compartments 30 6 and 7 by a centrally disposed shelf 8. This shelf is as wide as the widest portion of the sides and a shelf 9 of similar width is supported on the bottom member 4 and is suitably secured thereto. The two shelves forming the bottom 35 portions of the respective cabinets also form supports for the paper articles, such as towels, etc., placed in the compartments. Each compartment is normally closed by a cover and the covers are indicated at 10 and 11. The covers are 40 hingedly secured to the top and bottom sections, as indicated at 10a and 11a, and each cover may be provided with a key actuated lock 12 to prevent tampering by unauthorized individuals. The side portions of the respective covers are 45 angularly cut to conform to the cut portions of the sides of the cabinet, and when the covers assume closed position, their front faces will be parallel to the back panel so as to give the cabinet a uniform thickness throughout. The paper 50 placed in the respective compartments, whether it be towels, napkins, or otherwise, is dispensed or removed through slots 14 and 14a formed in the respective cover sections. These slots extend from end to end of the cabinet and are so 55.

wide that the folded sheets of paper can be readily removed. The folded sheets of paper forming the towels, or otherwise, are supported on their edges as shown in Fig. 2, when the cabinet assumes a horizontal position, as shown in Fig. 1, and they are supported on their ends when the cabinet is placed in a vertical position as shown in Fig. 4.

Means are provided for maintaining the towels in a forward position where they may be readily grasped and removed through the slots 14 and 14a. Follower or pusher plates have been provided for this purpose, such as indicated at 15 and 15a; these plates being preferably gravity actuated. This is accomplished as follows: By referring to Figs. 2 and 3, each follower plate is supported by a downwardly inclined pivoted link 16; the inner or rear end of which is pivotally attached to the rear panel A at 17 (Fig. 2), and the front or lower end is pivoted to the rear side of its respective follower plate, as at 18. By such an arrangement the link 16, weighted with the follower at its forward free end, will tend to swing forward by gravity and away from the back of the cabinet and maintain the paper articles in proper position and to automatically advance them as they are removed one by one.

As shown in Figs. 1 and 4, the cabinet may assume either one of two positions. First the position in which the dispensing slots 14 are horizontally disposed, see Fig. 1, and secondly a position in which the slots are vertically disposed as shown in Fig. 4. The gravitational action of the follower plates is not affected by such change in position and the towels, or other paper articles employed, will, accordingly, feed forward regardless of the position of the cabinet.

A cabinet constructed as here disclosed has many advantages: First of all, it permits the use of wide dispensing slots and by using such slots paper towels, toilet tissue, paper napkins, etc., may be dispensed and they may be interleaved and single-folded or they may be multi-folded as diagrammatically illustrated in Figs. 6, 7 and 8. If in using interleaved towels, the thread of interleaving is lost, it is of no importance as the free ends of the folded articles are readily accessible through the wide dispensing slots in the front and can be easily removed. When refilling a cabinet, interleaving of the bottom towel of a new package with the top towel remaining from the previous package in the cabinet is accordingly unnecessary. By supporting the paper articles either on their edges or ends as illustrated, frictional resistance when removing the articles through the dispensing slots is reduced to a minimum and tearing and wasteful dispensing is entirely obviated. A simple form of gravitation actuated follower plate may be employed and the mechanism is thus simplified and manufacturing cost reduced. By cutting away the side sections as illustrated, a large opening will be pre-

sented when the covers are open and reloading and filling of the cabinets is easily and quickly accomplished. By providing an intermediate shelf the cabinet is divided into two compartments, thereby doubling the capacity of a cabinet of this character, and furthermore, permitting simultaneous dispensing or removal of the paper articles contained. Practically all friction is obviated and positive dispensing from the first to the last towel is assured. The distance the cabinet projects from the wall may be materially decreased and a neater construction and generally improved appearance is assured.

While certain features of the present invention are more or less specifically described, I wish it understood that various changes may be resorted to within the scope of the appended claims. Similarly, that the materials and finish of the several parts employed may be such as the manufacturer may decide, or varying conditions or uses may demand.

Having thus described my invention, what I claim and desire to secure by Letters Patent is:—

1. A dispensing device for paper towels and the like consisting of a cabinet adapted to receive a plurality of paper towels, each of which is individually supported, said cabinet having a wide dispensing slot formed therein and extending from end to end of the cabinet, a follower plate engageable with the paper towels to maintain them in position to be removed one by one from the discharge slot, and an arm pivoted to the follower plate at one end and to the cabinet at the other end to support the follower plate, the pivots at the opposite ends of the arm being disposed at a slight angle to a vertical line to cause gravitational movement of one end of the arm and the follower plate toward the dispensing slot.

2. In a dispensing device a cabinet having a compartment formed therein for the reception of paper towels and a slot through which the towels are dispensed, and gravitationally actuated means for moving the towels toward the slot, said means comprising an arm pivotally supported at one end to the cabinet, the longitudinal axis of said pivotal support being on a slight angle with relation to a vertical line to cause the free end of the arm to swing in a plane inclined with relation to a horizontal plane and to exert pressure to move the towels toward the dispensing slot.

3. In a dispensing cabinet for paper towels or the like comprising a cabinet, means for moving the towels toward the front wall of the cabinet, said means comprising an arm hinged at one end to the rear wall of the cabinet to lie in a substantially horizontal position against the rear wall, the hinge for said arm having its axis disposed at an angle to the rear wall whereby the free end of the arm will gravitate forwardly and downwardly.

HENRY L. SAMSON.
